Sidney Sanders.

United States Patent Office.

HENRY W. BAILEY, OF SPRINGFIELD, MASSACHUSETTS, ASSIGNOR TO HIMSELF AND WILLIAM C. BAILEY, OF SAME PLACE.

Letters Patent No. 75,662, dated March 17, 1868.

IMPROVEMENT IN DIES FOR MAKING HAMMERS.

The Schedule referred to in these Letters Patent and making part of the same.

TO ALL WHOM IT MAY CONCERN:

Be it known that I, HENRY W. BAILEY, of Springfield, in the county of Hampden, and State of Massachusetts, have made and invented certain new and useful Improvements in the Formation and Construction of Sockets; and I do hereby declare that the following is a full, clear, and exact description of the manner of forming and constructing the same, reference being had to the annexed drawings, making a part of this specification, in which—

Figure 1 is a longitudinal section, result of one heat, and

Figure 2 a perspective view, result of two heats.

Figure 3, a vertical section of the punch A and die B.

Figure 4, an end elevation of the die B.

Figure 5, a bottom view or plan of the punch; and

Figure 6, a plan of the die B.

Figure 7, a lateral or cross-section of the punch A and die B.

My invention relates to certain improvements in dies for the formation and construction of sockets on hammers, hatchets, adzes, or any tool having an eye, and provided with a socket around the same for the insertion and support of a handle.

As heretofore practised in the manufacture of such tools, a bar of iron or steel, of nearly the same width as the head and socket combined, is heated and punched to form the eye *e*, a small punch being first inserted, and larger ones successively, till the eye is of proper dimensions. As punches of five different sizes are usually employed, and heating is necessary at each successive punching, the forming of the eye thus requires five heats. The head *a* is then "cut down" at each end of the eye *e*, thus forming or leaving the socket *b*, which is afterwards "drawn out" a little on a mandrel and finished with swages. These latter operations require from two to four heats, thus necessitating from seven to nine heats in forming the eye and socket.

The dies invented by me are designed to obviate the necessity of heating so many times, and also of cutting away and wasting the stock in forming the socket; and in carrying out my invention, I provide a steel die, having across its face a groove, slightly wider and somewhat deeper than the respective width and depth of the bar of which the head *a* is to be formed; and about midway of the groove, but deeper, and below the same, I construct and provide the die with a matrix of about the same size and shape as the exterior of the socket to be formed therein. I also provide a punch, A, of the proper size and length to form the eye *e*, which punch I place in a "drop," and so arrange the die B that when the drop descends the punch falls directly in the middle of the matrix, but is prevented from touching the bottom by the shoulder of the punch A, Figure 7. I then heat a bar of iron or steel to a proper degree, and place it in the channel across the face of the die. I then raise the "drop" and let it fall, when the punch not only pierces the bar composing head *a*, thus forming the eye *e*, but at the same time drives a part of the stock or bar through into the matrix or die, and forms the socket *b*, as far as seen in fig. 1, which is a sectional view of the head, eye, and socket, resulting from one heat or operation.

Reheating the head *a*, I insert a cold-chisel in the hole formed by the punch, and at a blow I open the eye on the outer end of the socket. Removing the cold-chisel, I insert a mandrel in the eye, on the side opposite that on which the punch entered, and give the exterior of the socket the required form by means of swages, as seen in fig. 2.

The peculiarity of my invention consists in the employment or use of the punch and die herein described, for forming the socket *b* of the stock, removed in punching the eye *e*, and essentially accomplishing both at one and the same operation.

The advantages resulting are obvious. I save from five to seven heatings, and a large amount of valuable stock or material cut away and wasted by the old process in forming the socket.

The shoulders *m m* of the punch A pass down to and rest on the shoulders *n n* of the die B, and when so resting, the lower end, *o*, of the punch A does not entirely reach to the bottom of the die B, but leaves sufficient space to retain the metal, as described in another part of this specification.

Having thus described my invention, and how the same is to be performed, I wish to be understood that I do not claim the providing of any particular tool or implement with an eye and socket; nor do I intend to limit myself to steel as the substance of my punch and die, as some other material may be found to answer as well; but

What I do claim as new, and for which I desire to secure Letters Patent, is—

The combination of the punch A and die B, herein described, when constructed and operating substantially as and for the purpose set forth.

HENRY W. BAILEY.
